UNITED STATES PATENT OFFICE

112,389

DESIGN FOR AN ATTACHABLE PROJECTION LAMP

Harry P. Toppin, Rochester, N. Y., assignor to
F. A. Smith Manufacturing Company, Inc.,
Rochester, N. Y., a corporation of New York

Application October 10, 1938, Serial No. 80,346

Term of patent 3½ years

To all whom it may concern:

Be it known that I, Harry P. Toppin, a citizen of the United States, residing at Rochester, in the county of Monroe and State of New York, have invented a new, original, and ornamental Design for an Attachable Projection Lamp, of which the following is a specification, reference being had to the accompanying drawing, forming part thereof, and in which:

Fig. 1 is a side view;
Fig. 2 is a rear view; and
Fig. 3 is a front view of said attachable projection lamp showing my new design.

I claim:

The ornamental design for an attachable projection lamp, as shown.

HARRY P. TOPPIN.
